UNITED STATES PATENT OFFICE.

ELNATHAN COLE, OF LOS ANGELES, CALIFORNIA.

SIGNAL-DISPLAY.

1,274,007.

Specification of Letters Patent. Patented July 30, 1918.

Application filed January 17, 1917. Serial No. 143,191.

To all whom it may concern:

Be it known that I, ELNATHAN COLE, a citizen of the United States, residing at Los Angeles, in the county of Los Angeles and State of California, have invented a new and useful Signal-Display, of which the following is a specification.

My invention relates to signal displays, and is more particularly a display for automobiles and the like by means of which the driver may indicate to the following traffic the direction about to be taken by the machine upon which the display is mounted.

One of the main objects of my invention is to produce a display of the character described of compact form, and of simple construction and operation, it being another object of my invention to produce a device of the class described in which the ordinary tail light, the number plate, and signal displays, are combined in one compact device.

Referring to the drawings, which are for illustrative purposes only:

Figure 1 is a diagrammatic rear view of an automobile, showing a signal display thereon embodying a form of my invention.

Fig. 2 is an enlarged face view of the signal display.

Fig. 3 is a vertical sectional view of the signal display shown in Fig. 2.

Fig. 4 is a side elevation of the same.

Fig. 5 is an enlarged sectional view taken on line 5-5 Fig. 3.

Fig. 6 is a face view of the controlling device for the signal display.

In the form of my invention shown, the device consists of a flat case 10 having a front wall 11 and a rear wall 12 spaced apart therefrom, the front wall 11 terminating at its edges in rearwardly extending walls 13, and the rear wall 12 terminating at its edges in forwardly extending walls 14, the walls 13 and 14 abutting against each other, thereby forming side, top, and bottom walls for the case 10. The walls 13 are cut away on each side of the case, as indicated at 15, to form slots 16 in the side walls of the case through which are operated display arms 17 and 18. The rear wall 12 is provided with two circular openings 19 and 20, the edge of the wall 12 around such openings terminating in forwardly extending circular flanges 21 and 22, the faces of which are finished to form seats adapted to be slidably engaged by extensions 23 and 24 formed on the arms 17 and 18 respectively. The

openings 19 and 20 are directly behind similar openings 25 and 26 respectively formed in the front wall 11 of the case, such openings 25 and 26 having secured therein glass plates 27 and 28, respectively, such plates being secured therein in any well known manner, and constituting, with the illuminating means hereinafter described, direction lights. The rear wall 12 is also provided with a central opening 30, the edges of the rear wall 12 about such opening terminating in a forwardly extending circular flange 31 which extends through the front wall 11 and has attached thereto, by means of screws or pins 32, a cylindrical box 33 in the outer end of which is mounted, in any suitable manner, a lens 34, preferably of red glass, constituting a tail light for the automobile, the illuminating source of which is an electric bulb 35 mounted in a casing 36, which casing 36 is secured in any suitable manner to the rear wall 12 of the case 10. The casing 36 is of sufficient width to form a light chamber 37, from which chamber light from the bulb 35 is projected through the openings 26 and 26 of the case.

40 designates a number plate of any common form and construction secured to the front wall 11 of the case 10 directly below the tail light and direction lights 27 and 28. The number plate in the form shown is secured to the wall 11 by means of screws or bolts 41 which extend through the front and rear walls 11 and 12, thereby also serving to hold the case together. Similar screws or bolts 42 are arranged at the top of the case for the purpose of holding the top portion of the case together. The upper portion of the number plate is secured to the front wall 11 of the case by means of suitable screws 43. 44 designates an opening in the underside of the box 33, such openings having a white glass 45 mounted therein in any suitable manner, light from the bulb 35 passing through the glass 45 to the number plate 40, thereby illuminating the same at night when the bulb 35 is illuminated.

The arms 17 and 18 constitute manually operated display means for indicating the direction in which the automobile is about to turn, such arms 17 and 18 being pivotally mounted on pins 47 and 48 respectively, and in the form shown the arms 17 and 18 are made in the form of hands terminating in extensions 23 and 24, which may be designated as wrist portions. Each arm 17 and

18 has pivotally connected thereto links 49 and 50 respectively which in turn are pivotally connected to levers 51 and 52 respectively, which levers 51 and 52 extend downwardly to a central point below the circular flange 31 of the rear wall 12 of the case where the lower ends of the levers 51 and 52 are pivotally mounted on a pin 53 mounted in any suitable manner on the rear wall of the case 10. The levers 51 and 52 are connected by wires 54 and 55 respectively to hand levers 56 and 57 respectively mounted on a bracket 58, which, in the form shown, is mounted upon the tubular casing 59 of the post of the steering wheel 60, the wires 54 and 55 passing through flexible wire cables 61 which extend from the case 10 in which they are mounted in lugs 62 to the bracket 58 in which the other ends of the flexible cables are mounted in lugs 63 formed on the bracket 58.

The device is used in the following manner:

The arms 17 and 18 are for the purpose of giving a visible indication during day light of the direction which the machine is about to take, the display of the arm 17, as shown in Fig. 2, being an indication that the machine is about to turn to the left, and the display of the arm 18, as indicated in dotted lines in Fig. 2, being an indication that the machine is about to turn to the right. Assuming that the machine is about to turn to the left, the operator pushes the lever 56 downwardly, which exerts a pull on the wire 54. This depresses the lever 51 and through the medium of the link 49 swings the arm 17 from the position shown in Fig. 3 to the position shown in Fig. 2, in which position the arm 17 remains until the turn has been made by the machine and the hand lever 56 returned to normal position, at which time the arm 17 will return to the position shown in Fig. 3. If it is desired to turn to the right, the arm 18 is operated through the medium of the hand lever 57 in the same manner as that heretofore described in relation to the operation of turning to the left.

At night, when the tail light 34 is illuminated, by means of the bulb 35, the direction lights, that is lights 27 and 28, which may be of green or any desired color, are dark, due to the fact that the wrist portions 28 and 24 of the arms 17 and 18 are over and close the openings 19 and 20 respectively, the wrist portions being adapted to seat on the circular flanges 21 and 22 heretofore referred to. This is the condition of the display when the tail light is illuminated and the machine is traveling in a straight direction. If the machine is about to turn to the left, the hand lever 56 would be operated as heretofore described, the arm 17 would be thrown into the position shown in Fig. 2, and the wrist extension 23 of the

arm 17 would move downwardly, thereby exposing the opening 19 through which light from the light chamber 37 would pass through the side or direction light 27, thereby indicating by a colored light to the left of the tail light that the machine is about to turn to the left. After such turn has been made, the return of the hand lever 56 to normal position would bring the arm 17 into the position shown in Fig. 3, the extension 23 or wrist portion of the arm 17 closing the opening 19 and thereby concealing the direction of the light 27. The turning of the machine to the right would be indicated in the same manner as that described with reference to indicating a turn to the left, by the operation of the hand lever 57 heretofore described. If the machine is about to stop, both hand levers 56 and 57 may be operated, in which case both arms 17 and 18 would move into the display position, and both direction lights, should it be at night, would be displayed on each side of the tail light 34.

I claim as my invention:

1. A signal display comprising a case, direction lights in said case, a display arm for each direction light pivotally mounted in said case, an extension formed on each arm, and means for operating either of said arms to display the arm and move the extension thereon to disclose its associated light.

2. A signal display comprising a case having an opening in each side thereof, a tail light in said case, said case having a direction light opening at each side of the tail light, a display arm pivotally mounted in said case for each direction light opening, a lever for each arm, a link for each lever pivotally connecting one end of the lever to its associated arm, and means for independently operating either of said levers to move its associated arm through its associated opening in the side of the case and simultaneously therewith uncover its associated direction light opening.

3. A display device comprising a case formed of front and rear walls, said rear wall having a tail light opening and direction light openings formed therein, a casing secured to said rear wall spaced apart therefrom and extending over said respective openings, a lamp mounted on said casing in the tail light opening of said case, a circular flange formed on the rear wall of said case about the tail light opening therein and extending through the front wall thereof, a box mounted on the front end of said flange, said box having an opening in the bottom portion thereof, a glass in said opening, a lens mounted in the front of said box, the front wall of said case having openings therein in alignment with the openings in the rear wall, a glass in each opening in the front wall, an arm for each direction open-

ing pivotally mounted in the case, means for operating either of said arms to display said arm, an extension on each of said arms adapted to close its respective opening in 5 the rear wall of the case, means for operating either of said arms to display the arm and uncover its respective direction light opening in the rear wall of the case, and a number plate on said case below the opening 10 in said box.

4. A signal display comprising a case having an opening in each side thereof, a tail light centrally disposed in said case, a direction light opening in said case at each 15 side of the tail light, a display arm pivotally mounted in said case for each direction light opening, means for directing the light from the tail light through the direction light openings, an extension on each of said 20 arms extending over its associated direction

light opening, and means for independently operating either of said arms to display the operated arm and uncover its associated light opening.

5. A signal display comprising a case having a tail light opening and a direction light opening at each side of the tail light opening, a single source of illumination in said case for said openings, a display arm covering each direction light opening to prevent 25 the passage of light through its associated opening, and operating means whereby either of said arms may be moved to uncover its associated direction light opening and extend a portion of the arm beyond the 30 case.

In testimony whereof, I have hereunto set my hand at Los Angeles, California, this 2nd day of January, 1917.

ELNATHAN COLE.
